NOZZLE

Joseph E. Kennedy, New York, N. Y., assignor to
 Kennedy-Van Saun Mfg. & Eng. Corporation,
 New York, N. Y., a corporation of Delaware

Application February 20, 1939, Serial No. 257,447

4 Claims. (Cl. 299—150)

This invention relates to valve controlled nozzles to admit fluid, such as air or steam under pressure, into a container to aerate and discharge pulverulent, granular and the like materials from the container, and is an improvement on the nozzle disclosed in my co-pending application filed November 21, 1936.

In nozzles of this character the outlet is controlled by a valve normally urged to position to close and shut off the outlet from the container, and the valve is actuated to nozzle outlet opening position and air discharged from the nozzle by the pressure of the air admitted into the nozzle casing. The nozzles are mounted upon the bottom of the container, which is of hopper form, and the air discharged from the nozzles along the wall of the container to not only aerate the material in the container but also release from the container wall material, particularly cement or flour, which may have adhered thereto and thus assure the discharge of all the material from the container. The valve mechanism in my hereinbefore mentioned application includes a member of resilient material, such as rubber, for the valve to seat against to assure closing and shutting off the nozzle from the container. The resilient member is exposed to the interior of the container and the valve is carried by a stem provided with a longitudinal recess or recesses to discharge the air in a predetermined direction or directions from the nozzle. Due to exposure of the resilient member to the interior of the container there is a possibility of the material lodging on the same with the result that the valve will not positively seat thereon and when the air under pressure is shut off from the nozzle the pressure in the container causes the material to pass from the container through the nozzle outlet into the nozzle. Furthermore, due to the valve spring resisting the actuation of the valve to outlet opening position by the pressure of the air there is effected a distortion of the resilient member and a resultant uncontrollable discharge of the air from the nozzle.

It is an object of the invention to provide in a nozzle of this character improved adjustable outlet control valve means to assure the discharge of a stream of air under pressure in predetermined direction at a right angle and perpendicular to the axis of the nozzle, and to provide means to rotatably adjust the same from the exterior of and without removing the nozzle from the container to cause the stream to be discharged from the nozzle in any desired angular direction along the wall of the container.

It is a further object of the invention to provide improved outlet control valve means for nozzles of this character including a member of resilient material, such as rubber, to assure positively sealing the outlet, and the valve means arranged to carry and confine the resilient member within the valve means whereby it will not be exposed to the interior of the container.

It is another object of the invention to provide an improved nozzle of this character including a casing having an inlet for the admission of air under pressure into the casing and a tubular projecting outlet portion through which to discharge the air from the nozzle, and valve means including a stem extended through the tubular outlet portion into the casing, said stem carrying a cup member slidably engaging the tubular outlet portion exterior of the casing and having a recess extended inwardly from the edge of the flanges thereof to constitute the discharge orifice of the nozzle adapted to be placed into and out of communication with the bore in the tubular outlet portion and vary the area of the orifice and discharge of a stream of air from the nozzle in a direction perpendicular to the axis of the nozzle, and said cup member carrying therein a member of resilient material adapted to be seated against the end of the tubular outlet portion of the casing to positively seal the discharge orifice from the casing and arranged to direct the air to the discharge orifice, and the provision of means to rotatably adjust said cup member about the tubular outlet portion to position the discharge orifice to discharge a stream from the nozzle in different angular directions relative to the axis of the nozzle.

Other objects and advantages of the invention will hereinafter appear.

In the drawing accompanying and forming a part of this application,

Figure 1 is a longitudinal section of a nozzle embodying the invention and showing the parts in normal position with the valve mechanism closing the nozzle outlet.

Figure 2 is a view similar to Figure 1 but showing the valve mechanism actuated to open the nozzle outlet; and

Figure 3 is a cross section taken on the line 3—3 of Figure 1 looking in the direction of the arrows.

In carrying out the embodiment of the invention illustrated in the drawing there is provided a tubular body or casing 4 externally screw threaded at the opposite ends, as at 5 and 6. The screw threaded portion 6 is adapted for connection with a screw threaded opening in the wall

of a container, as at 1. A coupling member 8 having a bore of two diameters has threaded connection at the bore portion of larger diameter with the threaded end 5 of the body and the portion of least diameter screw threaded for connection of a conduit for conducting a fluid, such as air or steam under pressure, from a source thereof axially into the body 4.

The bore of the body 4 at the end of the screw threaded portion 6 is arranged with a portion of reduced diameter to provide a shoulder at said end of the bore, and shown as effected by a ring 9 engaged in the end of the body and secured therein by suitable means, as by welding, as shown at 10.

A sleeve or tubular outlet member 11 is mounted in the body with a portion 11' extended through and projecting from the end of the body. The inner end of said member is of increased diameter relative to the portion 11' and substantially equal to the internal diameter of the body and providing said member with a shoulder opposed to the shoulder formed by the ring 9 to prevent movement of said outlet member outwardly from the body 4, a packing gasket 12 of suitable yielding material, such as rubber, being interposed between said shoulders to provide a fluid tight connection between said parts. The external diameter of the projecting portion 11' of the outlet member 11 is reduced to a diameter less than the internal diameter of the ring. The outlet member 11 is urged toward the ring 9 by a sleeve 13 having an external diameter substantially equal to that of the bore in the body 4 and loosely engaged therein and of a length to extend beyond the end 5 of the body 4 opposite the outlet member 11. A band 14 of yielding material, such as rubber, of a width equal to or slightly greater than the portion of the sleeve projecting from the end of the body 4 is interposed between said projecting portion of the sleeve and the coupling member 8, and a fluid tight seal is provided between said sleeve, the body 4 and coupling member 8 by said annular band 14 and a gasket 15 of yielding material, such as rubber, interposed between the ends of the sleeve 13 and the band 14 and the shoulder formed by the threaded opening of reduced diameter in the coupling member 8. By screwing the coupling member 8 onto the body 4 a compression force is applied to the gasket 15 and the band 14 which in turn is transmitted through the sleeve 13 to the outlet member 11 and thereby applying a compression force to the gasket 12 and providing a fluid tight joint between the outlet member 11 and the ring 9.

To control the discharge of air from the body through the outlet member 11 in a stream directed at a right angle and perpendicular to the axis of the nozzle, a cup member 16 is mounted on the end of a stem 17 by engaging a reduced end of the stem in an opening axially of the cup member and securing it thereto by suitable means, as by welding, as shown at 18. The cup member 16 is arranged exteriorly of the outlet member 11 and the stem is extended through the bore in said outlet member into the body 4, the stem being of less diameter than said bore, as shown. The flange of the cup member slidably engages the projecting portion 11' of the outlet member and is shown as telescoping thereover. An annular member 19 of yielding material, such as rubber, is confined within the cup member 16, a peripheral portion of which member is of a thickness less than the depth of the

flange of the cup member and is engaged upon a portion of reduced diameter 17' of the stem and retained thereon in abutting relation to the shoulder formed by said reduced portion by the cup member. The outer face of the yielding member 19 declines slightly from the periphery toward the center thereof, as shown at 19'. The member 19 has a portion 19a of arcuate form in cross section projecting from the inner end and disposed about the opening therein through an arc somewhat greater than 180 degrees, the outer surface of said projecting portion extending parallelly of the axis of said member 19 and the inner face converging inwardly from the end to the opening, as at 19b, said projecting portion engaging a recess in the wall of the bore in the outlet member extended inwardly from the end of the projecting portion 11' to an extent equal to the length of said projecting portion 19a. The flange of the cup member 16 is provided with a recess 20 shown as extended inwardly from the edge of the flange to or slightly beyond the annular portion of the yielding member 19, said recess constituting an outlet orifice and the resilient member 19 is arranged within the cup member with the projecting portion 19a disposed diametrically opposite said recess. The resilient member 19 is adapted to be seated against the end of the outlet member 11 to seal the same from the cup recess or discharge orifice 20 which discharge orifice in said position of the parts is covered by the outlet member 11. The cup member with the member of yielding material is normally urged to position to engage the yielding member with the end of the outlet member by a spring 21 coiled about the stem 17 within the tubular body 4 and confined between the outlet member 11 and a head 22 fixed to the end of the stem within the body, the head being of less diameter than the body and the stem of a length so that the head in said position of the parts will be in spaced opposed relation to the inlet in the coupling member 8, as shown in Figure 1.

To limit the outlet opening movement of the valve means and maintain the flange of the cup member 16 in sliding engagement with the projecting portion 11' of the outlet member in all positions thereof, and to also hold the valve parts against rotative movement to discharge the stream from the recess or discharge orifice 20 in predetermined direction perpendicular to the axis of the nozzle, diametrically opposite slots 23 are extended into the end of the sleeve 13 opposite the end engaging the outlet member and in which slots the ends of a pin 24 extended through the head 22 slidably engage.

By the construction of the parts described the resilient member 19 when seated against the end of the outlet member 11 under the influence of the spring 21 and the pressure of the material in the container also serves to exert a closing pressure upon the cup member 16, thus positively sealing the outlet member through the discharge orifice 20 from the container and preventing material entering from the container into and choking the nozzle. Also by the arrangement of the parts the valve mechanism may be readily removed from the tubular body or casing 4 for inspection or renewal of parts without removing the body from the container and which is effected by removing the coupling member 8 and withdrawing the parts through said end of the body.

In operation the air under pressure admitted

into the body 4 through the inlet opening in the coupling member 8 and the air passing from the body through the space about the stem 17 in the outlet member 11 exerts a force upon the head 22 and the cap member 16 through the resilient member 19 to actuate the valve means against the action of the spring 21 to move the resilient member 19 out of engagement with the outlet member 11 and open the discharge orifice 22 and discharge the air therethrough from the outlet member, as shown in Figure 2. The actuation of the valve means and extent of opening the discharge orifice 20 to the outlet member 11 is in accordance with the pressure of the air. By the arrangement of the declining surface 19b on the projecting portion 19a of the resilient member 19 relative to the discharge orifice 20 the air passing through the outlet member 11 is directed toward the discharge orifice, and by the arrangement of the engagement of said projecting portion 19a with the outlet member the possibility of air passing through the contacting parts into the nozzle is reduced to a minimum. Also by the arrangement of declining the outer end of the resilient member 19 the inherent resiliency of the material of said member tends to urge the same into sealing engagement with the outlet member 11.

It is desirable and essential that the air be discharged from the nozzle 20 in predetermined direction, and under different conditions it is desirable to discharge the stream in different directions from the nozzle relative to a wall of the container. To indicate the position of the discharge orifice 20 and direction of discharging the stream from the nozzle the head 22 is provided with an indicator notch 25, said notch being arranged in line with the recess 20 in the flange of the cup member 16. By the arrangement of loosely mounting the sleeve 13 in the body 4 and the pin and slot connection 23, 24 between the head 22 and said sleeve, the valve mechanism may be rotatably adjusted about its axis and adjust the discharge orifice 20 to different angular positions relative to the axis of the nozzle.

Having described my invention, I claim:

1. In a nozzle including a casing having an inlet to admit air under pressure into the casing and an outlet through a tubular portion projecting from the casing, valve means for controlling the outlet and discharge of air through the casing, comprising a cup member slidably engaging the projecting portion and having a recess in the flange thereof, a member of yielding material in the cup member adapted to seat against the end of the projecting portion and seal the outlet, said cup member being normally urged to position with the projecting portion engaging the yielding member and the projecting portion covering the recess in the flange of the cup member and co-operating with the cup member to seal said yielding member therein, and said valve means actuated by the pressure of the air admitted into the casing acting on the yielding member in the cup member to unseat the yielding member from and place the flange recess in communication with the projecting portion to discharge the air through said flange recess in a stream laterally from the casing perpendicular to the axis of the valve means.

2. In a valve controlled nozzle including a casing having an inlet to admit air under pressure into the casing and having a tubular outlet portion projecting from the casing, valve means to

control the outlet and discharge of air through the casing comprising a stem of less diameter than and extended through the outlet portion into the casing, a cup member carried by the stem exterior of the casing with the opening opposed to and slidably engaging the tubular portion and having a recess in the flange, a member of resilient material in the cup member with an annular portion at the periphery disposed within the recess adapted to seat against the end of the outlet portion and seal the outlet, a spring normally urging said valve means to position with the resilient member engaging the end of and the cup recess covered by the outlet portion, and said valve means adapted to be actuated against the action of the spring by the pressure of the air admitted into the casing acting on the resilient member in the cup member to unseat the resilient member from and uncover the recess by the outlet portion and discharge the air through the flange recess in a stream laterally from the casing perpendicular to the axis of the valve means.

3. In a nozzle, a tubular body, a tubular outlet member mounted in and extended through one end of the body, a coupling member having fluid tight connection with the opposite end of the body and adapted to admit air under pressure axially into the body, and valve means for controlling the discharge of the air through the body comprising a cup member slidably engaging the outlet member exterior of the body and having a recess extended inwardly from the edge of the flange thereof to constitute a discharge orifice adapted to be covered and uncovered by and placed out of and into communication with the outlet member and discharge the air from the nozzle in a stream laterally and perpendicular to the axis of the nozzle, a stem fixed at one end centrally within the cup member extended into the body through and having a diameter less than the opening in the outlet member, a member of resilient material confined in the cup member having an annular peripheral portion of less thickness than the depth of the cup flange adapted to engage the end of and seal the outlet member, said resilient member having a segmental portion extended centrally therefrom within said peripheral portion slidably engaging in the outlet member and arranged to direct the air laterally from the outlet member to the flange recess in the cup member, a spring urging the valve means to position to cover the valve recess by and seat the annular portion of the resilient member against the outlet member, means to limit the opening movement of the valve means and maintain the cup member at all times in sliding engagement with the outlet member and rotatably adjust the valve means about the axis of the nozzle to position the discharge orifice in different positions about the outlet member to discharge the stream therefrom in different directions perpendicular to the axis of the nozzle, and said valve means adapted to be actuated against the action of the spring by the pressure of the air admitted into the body acting on and moving the resilient member out of engagement with and open the discharge orifice to the outlet member.

4. In a valve controlled nozzle including a casing having a tubular outlet portion projecting therefrom and means connected to the casing opposite the outlet portion to connect the casing to a source of and admit air under pressure into the casing, valve means for controlling the dis-

charge of air through the outlet portion, comprising a stem of less diameter than and extended through the outlet portion into the body, a cup member having a recess extended into the end of the flange fixed centrally thereof to the end of the stem exterior of the casing with the open end opposed to and the cup flange slidably engaging the outlet portion to cover and uncover the recess by the outlet portion to shut off and open communication between said recess and said outlet portion and control the discharge of air through said recess from the casing, a spring normally yieldingly urging the stem with the cup member to position with the flange recess covered by and out of communication with the outlet portion of the casing, and said stem with the cup member adapted to be actuated by the pressure of the air admitted into the casing act-

ing on the cup member against the action of said spring to position the cup member to uncover the flange recess and open communication between the outlet portion and said recess and discharge the air in a stream through said recess laterally and perpendicular to the axis of the nozzle, and a member of resilient material in the cup member having an annular portion at the periphery of less thickness than the depth of the cup flange adapted to seat against the end of the tubular outlet portion and having a segmental portion projecting therefrom within said annular portion disposed opposite the flanged recess slidably engaging in said outlet portion and arranged to direct the air from said outlet portion laterally to said flange recess.

JOSEPH E. KENNEDY.
